PRODUCE DISPLAY TRAY

Virgil T. Pringle, Indianapolis, Ind.

Application March 7, 1956, Serial No. 570,069

2 Claims. (Cl. 229—22)

The invention herein set forth is embodied in a tray of generally triangular form intended to be used to carry and display a limited number of produce articles such as peaches, plums, and most particularly, tomatoes such as may be grown in a hot house where the tomatoes will be of relatively uniform size.

For the sake of economy, the tray may be made out of cardboard, although the invention is not necessarily limited to that material. It is desirable that the material be flexible and yet sufficiently rigid to stand up under the intended usage as above indicated for the period required from the time the produce is packed in the tray until it is displayed and finally delivered to the consumer.

One of the primary purposes of the invention is to provide a tray having a contour of the encircling wall which will receive the produce without tending to distort the articles of the produce when those articles bear firmly against the wall. In this regard, the tray is so constructed under the invention as to provide a degree of yielding of the wall under inside pressure from the articles of the produce, while, at the same time, the articles are prevented from being forced into sharp corners of the wall.

A further important object of the invention is to provide a structure which may be set up from a blank state with the minimum number of operations, and which will retain its set up shape even though the trays may be thrown promiscuously into boxes or containers pending their use.

The invention contemplates the use of a transparent sheet of covering and protecting material and this sheet will be carried down around the outer side of the encircling walls of the tray and held in position by means of a flexible band such as a rubber band stretched around the outside of the cover and forcing that cover inwardly and holding it against the encircling wall from the outside, and doing so in such a manner that the band will not be displaced accidentally, but only upon positive manipulation thereof.

In regard to the retaining of the band, it is a further purpose of the invention to provide longitudinal slots across the corners of the retaining wall, and into which slots there is a tooth extending and under which tooth the band may be positioned so as to not only retain the cover over the tray, but also do so in such a manner that the outside corners of the wall will not be under direct pressure of the band, and hence will maintain a more or less angular shape.

These and many other objects of the invention will become more apparent to those versed in the art in the following description of one particular form of the invention as illustrated in the accompanying drawings, in which

Fig. 1 is a view in top plan of the tray embodying the invention;

Fig. 2 is a view in side elevation of the tray in which tomatoes have been packed and a cover applied thereover;

2

Fig. 3 is a view in plan of the tray blank; and

Fig. 4 is a detail in section on the line 4—4 in Fig. 1. Referring to Fig. 3, a blank generally designated by the numeral 10 is formed to have a base or a floor

5 area shaped generally in the form of an equilateral triangle, being designated by the numeral 11. As will be noted, the corners are rounded by the arcuate boundary lines 12, 13, and 14. The lines 12 and 13 terminate by common ends on a score line 15 which forms the base 10 line of a side wall strip 16. The strip 16 extends by one end portion 17 by a base line 18 coinciding with the score line 15, and this base line 18 intersects approximately with a corresponding line 19 of a second side wall strip 20 which is an integral part of the base 11, 15 having a score line 21 defining the base line 19 across the side of the base 11. As indicated in Fig. 3, there is a slight clearance between the outer end of the line 18 and the line 19, this clearance being emphasized for the sake of clearness, and the line 18 may be extended 20 entirely to the line 19 to intersect, although that is not absolutely essential. It is desired however that the line 18 closely approach the line 19 as indicated so as to give as great as possible length to the line 18 from its intersection of the line 12 beyond the base 11.

25 A third side wall strip 22 is provided along the third side of the base 11, and defined by a score line 23 which coincides with the base line 24. The line 19 of the strip 20 closely approaches the line 24 of the strip 22. Likewise the line 24 of the strip 22 closely approaches the base line 18 of the strip 16. The strip 16 terminates by its end portion 17 in a straight line 25 which is normal to the base line 18. Likewise the strips 20 and 22 terminate in corresponding end portions by the end lines 26 and 27 respectively both normal to their 30 base lines 19 and 24. The side wall strip 16 is provided with an arcuate slit 28 extending from the base line 18 and slightly beyond the center of the strip 16 in respect to its base line 18 and the top edge 29. This slit 28 defines a tongue 30, the tongue being preferably roughly 35 rounded at its outer end portion by being cut away as at the line 31 adjacent the base line 18 and the line 32 intersecting the outer or relative end and eventually the upper line 29.

A score line 33 extends across the side wall strip 16 40 at right angles to the base line 18, and the intersection of the score line 33 with the base line 18 is at the center of that length of the base line 18 which lies between the intersecting point A of the arcuate line 13 with the base line 18 and the point B which is the intersection 45 of the lines 24 and 27 of the side wall strip 22. The arcuate slit 28 is located outwardly beyond the point B as indicated in Fig. 3.

Centered on the score line 33 and spaced outwardly 50 from the line 18 is a longitudinally disposed slot cut through the strip 16, this slot being designated by the numeral 34. The slot 34 is provided with a pair of opposing teeth 35 and 36 with space intervening therebetween. The teeth 35 and 36 are centered on the score 55 line 33. This same strip 16 further has an arcuate slit 37 disposed intermediate the line 18 and edge 29, extending generally longitudinally of the strip 16 rather than transversely thereof. This arcuate slit 37 is located 60 outwardly to extend by an end portion from a line roughly drawn from the intersection point C of the lines 12 and 18.

In like manner, the side wall strip 20 is provided 65 with the generally transversely extending slit 38 extending from the line 19 adjacent the end 39 which is roughly rounded by the under line 40 and the upper line 41, thus forming from the side edge 19 a tongue 42. A score line 43 extends transversely across the strip 20 70 midway between the points D and E, the point D

being the intersection point of the lines 18 and 25 and the point E being the intersection of the lines 12 and 19. A slot 44 extends longitudinally of the strip 20 centered on the score line 43, and there are the teeth 45 and 46 centered on the score line 43 opposing one another from the opposite sides of the slot 44. Then this strip 20 has an arcuate slit 47 extending generally longitudinally of the strip 20, adjacent the intersection F of the lines 14 and 19.

The strip 22 is likewise formed to have an arcuate slit 48 extending generally transversely of the strip 22 from the line 24, defining a tab or tongue 49 at the end of the strip 22 adjacent the end 26 of the strip 20. A score line 50 extends transversely across the strip 22 at right angles to the line 24, this score line 50 being midway between the intersection point G of the lines 14 and 24 and the point H at the intersection of the lines 19 and 26. A slot 51 extends longitudinally of the strip 22 to be centered on the score line 50, and also centered on the score line 50 are the opposing teeth 52 and 53 extending one toward the other from opposite sides of the slot 51. Finally the strip 22 has an arcuate slit 54 which extends generally longitudinally of the strip 22 adjacent the point J as the intersection of the lines 13 and 24.

The locations of these various slits, score lines and slots, will become more important and understandable as this description proceeds in the setting up of the blank.

With a blank 11 formed as indicated and as illustrated in Fig. 3, the side strips 16, 20 and 22 are folded on their fold lines 15, 21, and 23 respectively to have those strips turned generally upwardly into the three side walls of the tray. The square end portions of these three side wall strips terminating in the lines 25, 26, and 27 are brought on the insides of the next adjacent strips.

Referring to Fig. 1, the strip 20 is turned upwardly on its score line 21, and its end portion designated by the numeral 60 is curved around on the inside of the strip 22, and the tab or tongue 49 is inserted through the slit 47 to bring the score line 50 substantially at the mid-point of the arcuate line 14 of the base 11. This leaves the line 26 end of the strip 20 exposed on the inside of the strip or wall 22 but firmly held against the inside by reason of the tab 49 being passed through the slit 47, and engaging the end 61 snugly of the arcuate line 47.

In like manner, the strip 16 is folded upwardly on the score line 15 to bring its end portion 17 inside of the strip 20 in an arcuate manner while the tab or tongue 42 is inserted and pushed downwardly through the arcuate slit 37 to bring the arcuate line 38 snugly against and along the end 63 of the slit 37. This operation brings the end line 25 on the inside of the wall 20, without being secured thereagainst. The tab end 39 is on the inside of the wall 16, from the slit 37 downwardly.

The tray is then completed in its set up form by carrying the end portion 65 of the strip 22 adjacent the end line 27 around on the inside of the strip 16, and placing the tab or tongue 30 downwardly through the slit 54 to leave the end portion 65 in an arcuate shape while the score line 33 takes on a more or less angular position, that is forming a vertical line from which the portions of the strip 16 extend in a somewhat rounded fashion.

It is to be noted that in the set up condition of the tray, the end portions 17, 60 and 65 curve around and extend upwardly from the base 11 across those zones adjacent the lines 12, 13 and 14, but spaced inwardly somewhat therefrom. On the other hand, the score lines defining fold lines 33, 43, and 50, are just outside of these arcuate corners 13, 12, and 14 respectively. This relationship is illustrated in Fig. 1. When the produce articles, for example tomatoes generally designated by

the numeral 66 are placed on the base or floor 11 of the tray, one tomato 66 will be placed in each one of the corners thereof to have the tomatoes bear against the freely extending wall end portions 17, 60, and 65, these portions being flexible and being forced outwardly if the tomatoes be of sufficient size, the important point being however that in so doing, there is a rounded corner which does not impose by the side walls extending therefrom flat spots on the tomatoes. As is indicated in Fig. 1, these walls 16, 20, and 22 tend by their very nature to bow outwardly by their top edges which further accommodates the tray to the shapes of the tomatoes. With one tomato 66 placed in each one of these corners, there is generally placed a third tomato on the top and centrally of the tomatoes resting on the floor 11. Then there is preferably employed a transparent cover 67 which is drawn down over the tomatoes and down around the side walls 16, 20, and 22 to extend below the line of the slots 34, 44, and 51, whereupon a rubber band 68 is brought around on the outer side of the cover 67 and positioned to carry the cover 67 inwardly of those slots so that the band in each instance as well as the cover is engaged at least under the upper teeth 36, 45, and 52, thereby effectively holding the band 68 against displacement as might otherwise be the case where these trays are placed one adjacent the other in display arrangement or in shipping cartons. The lower tooth 35, 46, and 53 respectively further aids in preventing the withdrawal of the band 68 and the portion of the cover 67 which has been carried into the slot in each instance by the band. Also the presence of this band 68 tends to yieldingly retain the side walls 16, 20, and 22 against over extension by their top edges from the triangular shape, and likewise comes into contact through the intervening cover portion 67 with the inwardly positioned wall end portions 17, 60, and 65. Thus the arcuate shaping of these inside wall end portions is supported by the rubber band in a yielding manner, while the walls themselves tend to maintain sharp corners on the fold lines 33, 43, and 50. Otherwise, should the band be bearing across the fold lines, the walls 16, 20, and 22 would tend to be bowed outwardly more rather than less. It is to be remembered that the end portions of these walls exposed on the inside of the tray are free to travel along the tray walls under the influence either of the tomatoes on the inside or the rubber band on the outside or both. These free ends of the walls are supported by the base or floor 11 extending outwardly thereunder. That is, these end portions can not be forced down below the top side of the floor 11.

Therefore while I have shown and described my invention in the one particular form, it is obvious that structural changes may be made, such as in the shaping of the tabs or tongues which interengage adjacent walls, and the like, all without departing from the spirit of the invention, and I therefore do not desire to be limited to that precise form beyond the limitations which may be imposed by the following claims.

I claim:

1. A paperboard tray comprising a generally triangular base; a generally straight wall hinged to each side of said base for a distance therealong and extending upwardly therefrom; each wall having a free length extending from each end thereof; one of said lengths of one wall being free of scoring and extending arcuately and unsecured throughout its extent around inside of the next adjacent wall length with its end edge in free, frictional, sliding engagement with the inner surface of said adjacent wall; said adjacent wall length having a vertical score line approximately equi-distant between the proximate ends of the hinge connections of said one and said adjacent walls, and about which line that adjacent wall length angularly bends; an open space between said arcuate length and said adjacent wall length of a maximum width at said score line; and means securing

a portion of said adjacent wall length to said one wall over its said hinge connection whereby the arcuate lengths are resiliently supported in the corners to provide a cushion for articles carried in the tray.

2. The structure of claim 1 in which each of said adjacent wall lengths has a slot therethrough centered on and extending transversely of said score line; there are opposing teeth on the margins of said slot, one tooth extending downwardly and the other tooth upwardly, and an elastic band extends around the outer 10 sides of said walls and across said slots inside of said teeth adjacent said arcuate lengths maintaining said band

intermediate the tops and bottoms of said walls, resiliently opposing travel of those lengths toward said score line.
